PISTON SKIRT EXPANDER

Leon A. Witter, Parma, Ohio

Application February 10, 1934, Serial No. 710,658

13 Claims. (Cl. 309—12)

This invention relates to expanding devices and more particularly to an improved device for expanding the skirt of a split skirt piston of the type commonly used in the internal combustion engines of automotive vehicles.

5 Aluminum alloy pistons having split skirts are in very extensive use. In a common form of this type of piston the skirt is secured to the head portion of the piston by two oppositely disposed webs 10 which webs also carry the piston pin bearings. Due to the fact that the skirt is secured to these webs on its opposite sides and free from the head and web at the other portions of the skirt, an unequal expansion occurs at different parts of 15 the circumference of the skirt. It has been found that when an engine reaches its normal operating temperature the skirt of the piston expands from its original cylindrical shape to a more or less elliptical shape. This, of course, causes an uneven wearing of the skirt which results in an 20 uneven bearing against the walls of the cylinder. When this occurs "piston slap" or knocking results, at least when the engine is cold. In order to overcome this difficulty pistons are now manufactured, the skirts of which are originally 25 ground in an oval or elliptical form so that when they expand upon being heated to operating temperature they become round and thus properly fit the walls of the cylinder.

30 A number of devices have been proposed, and are in extensive use, for expanding the skirt of a piston having a slotted skirt to increase the diameter of the skirt and make it fit the cylinder walls after it has been worn to such an extent 35 that knocking occurs. The devices of this type with which I am familiar are in the nature of expanding rings which fit inside the walls of the piston skirt and may be expanded by suitable means to cause an increase in the diameter of the 40 skirt.

It is among the objects of my invention to provide means for expanding the skirt of a slotted skirt piston whereby a worn piston may be made to properly fit within the cylinder. Other objects 45 of my invention are: the provision of a piston skirt expanding device which may be quickly and easily inserted in a piston and which may be set to give any desired degree of expansion of the piston; the provision of a piston skirt expanding 50 device which is of light weight and small size and which does not interfere with the normal operation of the piston or its associated parts; the provision of a piston skirt expanding device which is adapted to expand a worn piston and give the 55 skirt of the piston an elliptical shape whereby the

desired operating characteristics are obtained; the provision of a piston skirt expanding device which is adapted to expand the skirt of a piston without destroying the inherent resiliency of the slotted skirt; the provision of a piston skirt expanding device which is particularly susceptible to economical manufacture, which may be readily installed and which, once installed, will not become dislodged while the piston is in use.

5 The above and other objects of my invention will appear from the following description of several embodiments thereof, reference being had to the accompanying drawing, in which—

Figure 1 is an enlarged perspective view of my piston skirt expanding device showing the parts 10 in assembled position.

Figure 2 is a cross section taken on line 2—2 of Figure 5 and also showing portions of the wall of the piston skirt to which the expanding device is 15 attached.

Figure 3 is a longitudinal cross sectional view taken on line 3—3 of Figure 1 and illustrating the expanding device of Figure 1 with the parts 20 in the positions they assume when the device is installed in a piston.

Figure 4 is a detached view of the flexible slot- 25 ed tapered sleeve portion of my expander.

Figure 5 is a side elevation of a slotted skirt piston with one of my expanding devices installed 30 therein.

Figure 6 is a fragmentary view illustrating a portion of the skirt of a piston with my expanding device installed.

Figure 7 is a cross sectional view similar to Figure 3 but illustrating a slightly modified embodiment of my invention.

Figure 8 is a detached perspective view of the locking washer illustrated in Figure 7.

Figure 9 is a perspective view, approximately 35 full scale, of a modified form of my piston expander.

Figure 10 is a cross sectional view generally similar to Figure 2 but illustrating a different form of the sleeve member.

Referring now to Figure 1, my improved expanding device comprises a tapered slotted sleeve 1 preferably made of spring sheet steel or the like and having its edges 3 and 4 adjacent the longitudinal slot 2 turned back to form hook shaped lips or flanges which are adapted to engage the 45 edges of the slot in the piston skirt. A tapered plug 5, preferably of aluminum or other light weight metal, having a threaded aperture 6 extending longitudinally therethrough, is adapted to fit within the tapered sleeve 1. The diameter 50

55

and length of the plug 5 are preferably such that the large end of the plug projects out beyond the large end of the sleeve 1 when the inner surface of the sleeve and the outer surface of the plug are in contact. The screw 7 is adapted to have threaded engagement in the hole 6 of the plug 5 and is provided with an enlarged portion, preferably a slotted head 8, to facilitate adjustment of the expander and form a shoulder which 10 will coat with the sleeve 1 to draw the plug 5 into the sleeve. A lock washer 9 may be interposed between the underside of the head 8 of the screw and the small end of the tapered sleeve 1 and serves to assist in locking the screw in adjusted position.

Before installing my expanding device in a piston the edges of the slot in the piston skirt are chamfered as is clearly seen in Figure 2. Any suitable tool may be used for this purpose 20 but, as such tool does not form part of this invention, it need not be described here. Next the expanding device, with the parts assembled as shown in Figure 1, is slipped upwardly into the position shown in Figure 5 with the large end of the plug 5 toward the head of the piston and with the hook shaped lips 3 and 4 engaging the edges of the slot in the piston. Preferably the device is positioned with the center of the tapered sleeve lying substantially on a plane passing 30 through the centers of the piston pin bearings. Next, the screw 7 is rotated to draw the tapered plug 5 down into the sleeve 1. It will be seen that, as the plug 5 enters the sleeve 1 it will force the lips 3 and 4 apart increasing the width of the 35 slot 2 and forcing apart the edges of the slot in the piston. As the portions of the piston skirt adjacent the slot are anchored to the webs W (Figure 2) this expansion of the slot will cause the portions A and B of the piston (see Figure 5) 40 to swing outwardly about the points C and D (Figure 2) thus increasing the transverse dimension of the piston skirt and forming an oval shaped piston which possesses all of the advantages of a piston having a skirt originally ground 45 to such form.

As is seen in Figure 2 I preferably shape the tapered sleeve 1 so that the portions of the sleeve immediately adjacent the lips 3 and 4 and the slot 2 do not contact with the surface of the plug 5. Thus, when the expanding device is in position and the piston skirt walls have been expanded the function of the slot in the skirt is not destroyed as the walls of the skirt are still permitted a certain flexibility of movement due 50 to the fact that the sleeve 1 does not engage the plug 5 throughout its entire circumference.

In Figure 10, which is a cross sectional view similar to Figure 2, but illustrating a slightly different embodiment of my expander, the sleeve member is of an oval cross section and engages the plug 5, which is preferably of circular cross section, at the sides 17 and 18 thereof but is spaced from the plug member on what we may call the front 19 and the back portion 20 thereof. This arrangement provides for a somewhat more flexible movement than does the arrangement of Figure 2 but it will be understood that the function of spacing the walls of the sleeve from the surface of the plug at certain points is 60 the same in both of the illustrated forms, namely, to permit the slot in the skirt of the piston to perform its intended function after my expander device has been installed.

In Figure 7 I have illustrated a modified form 75 of my piston expander in which the underside of

the head 8' of the screw 7' is notched or serrated as seen at 10 and the washer 11 is formed with oppositely disposed projecting portions 12 adapted to fit in the serrations in the head 8' of the screw. The washer 11 is also formed with a lug portion 12' which projects into the slot 2 of the sleeve 1 and prevents relative rotation of the washer and sleeve. This washer and serrated head surface gives a ratchet action upon rotation of the screw to expand the piston skirt and provides an indication of the degree of expansion given to the piston skirt as well as preventing the loosening of the screw. A pin 13 is illustrated in Figure 7, this pin extending out from the body of the plug 5 into the slot 2 of the sleeve 1. This pin does not, however, extend beyond the edges of the lips 3 and 4 and serves merely to prevent relative rotation of the plug 5 and sleeve 1 thus insuring that the plug will be drawn into the sleeve upon rotation of the screw 7' in the proper direction.

As is seen in Figure 4 the ends of the flanges 3 and 4 at the large end of the sleeve 1 are preferably rounded off to prevent the hardened spring steel of the sleeve from digging into the relatively 25 soft metal of the piston and to facilitate the insertion of the device in the slot in the piston skirt. The ends of the flanges or lips 3 and 4 at the small end of the sleeve 1, however, have sharp edges which are adapted to dig into the 30 soft metal of the edges of the slot in the piston and effectively prevent accidental removal of the device.

In Figure 9 I have illustrated, in approximately full size, a modified form of my expanding device 35 in which the plug member 5 is provided with a transversely extending lug or flange 14 at its large end. This flange is adapted to engage the inner walls of the piston skirt when the device is installed and prevents the plug 5 from rotating 40 within the sleeve 1. When this flange 14 is used it will not be necessary to provide a pin 13 as illustrated in Figure 4.

My complete expanding device weighs less than one-half ounce and I have found that it does not 45 materially change the balance of the piston or in any way affect the operation of the vehicle engine except to improve the fit of the piston in the cylinder. A single size of expanding device may be used with a large range of sizes of pistons 50 and my expanding device can be used to expand the pistons any amount within the usual practical limits.

Although I have described in considerable detail the illustrated embodiments of my invention 55 it will be seen by those skilled in the art that variations and modifications may be made in the specific form of my piston expander without departing from the spirit of my invention. I do not therefore wish to be limited to the specific 60 form described and illustrated, but claim as my invention all embodiments thereof coming within the scope of the appended claims.

I claim:

1. A piston skirt expander including a tapered 65 sleeve member having a slot extending lengthwise thereof, said sleeve having lip portions adjacent said slot adapted to engage the edges of a slot in the skirt of a piston, a tapered plug fitting within said sleeve and means for drawing 70 said plug into said sleeve to vary the width of said slot in said sleeve.

2. In a piston skirt expander, a tapered, resilient sleeve slotted longitudinally and having a piston engaging lips adjacent the slot therein, a 75

tapered plug member disposed within said sleeve and means for moving said plug longitudinally of said sleeve.

3. In a piston skirt expander, a tapered sleeve slotted longitudinally having piston engaging lips adjacent the slot therein and adjustable means acting longitudinally of the sleeve and engaging the same for varying the distance between said lips.

4. In combination with a piston having a slotted skirt, a skirt expander disposed in the slot and adapted to vary the width thereof, said expander comprising a slotted sleeve member having lips removably engaging the edges of the slot in the piston and means for expanding the slot in said sleeve whereby the width of the slot in the piston will be increased.

5. In a piston skirt expander, a tapered, resilient sleeve slotted longitudinally and having piston engaging lips adjacent the slot therein, a tapered plug extending into said sleeve, said plug having a threaded aperture extending thereto, a screw having threaded engagement with said plug in said aperture and extending out of the small end of said sleeve, said screw having an enlarged portion on the end which extends out of the sleeve, said enlarged portion being adapted to engage the end of said sleeve whereby rotation of said screw in one direction will draw said plug into said sleeve and expand the slot therein.

6. In a piston skirt expander, a tapered, resilient sleeve slotted longitudinally and having piston engaging lips adjacent the slot therein, a tapered plug extending into said sleeve, said plug having a threaded aperture extending thereto, a screw having threaded engagement with said plug in said aperture and extending out of the small end of said sleeve, said screw having an enlarged portion on the end which extends out of the sleeve, said enlarged portion being adapted to engage the end of said sleeve whereby rotation of said screw in one direction will draw said plug into said sleeve and expand the slot therein, and means for locking said sleeve and plug against relative rotary movement.

7. In a piston skirt expander, a tapered, resilient sleeve slotted longitudinally and having piston engaging lips adjacent the slot therein, a tapered plug extending into said sleeve, said plug having a threaded aperture extending thereto, a screw having threaded engagement with said plug in said aperture and extending out of the small end of said sleeve, said screw having an enlarged portion on the end which extends out of the sleeve, said enlarged portion being adapted to engage the end of said sleeve whereby rotation of said screw in one direction will draw said plug into said sleeve and expand the slot therein, said plug having a laterally extending lug on its large end adapted to engage the wall of the piston skirt whereby relative rotary movement of the plug and sleeve is prevented.

8. In a piston skirt expander, a tapered, resilient sleeve slotted longitudinally and having

piston engaging lips adjacent the slot therein, a tapered plug extending into said sleeve, said plug having a threaded aperture extending thereto, a screw having threaded engagement with said plug in said aperture and extending out of the small end of said sleeve, said screw having an enlarged portion on the end which extends out of the sleeve, said enlarged end being adapted to engage the end of said sleeve whereby rotation of said screw in one direction will draw said plug into said sleeve and expand the slot therein, and a pin extending from the surface of said plug into the slot in said sleeve whereby relative rotary movement of said sleeve and plug will be prevented.

9. In a piston skirt expander of the type described, a resilient, slotted, tapered sleeve, a tapered plug disposed in said sleeve, said plug being formed to engage the inner surface of said sleeve except adjacent the slot in said sleeve and means for moving said plug into said sleeve to expand said slot.

10. In a piston skirt expander of the type described, a resilient, slotted, tapered, sleeve having lips adjacent the slot thereof adapted to engage the edges of the slot in the skirt of a piston, said lips having their ends adjacent the large end of the sleeve rounded off to facilitate insertion of the expander lips into the piston skirt slot and having their opposite ends relatively sharp whereby to dig into the metal of the edges of the piston skirt slot and resist removal of said sleeve from said slot, and means coacting with said tapered sleeve for varying the distance between said lips.

11. In an expanding device, a resilient slotted, tapered sleeve, a tapered plug disposed in said sleeve, said plug being shaped to engage the inner surface of said sleeve on areas extending lengthwise of the sleeve on the sides thereof and to be spaced from the sleeve adjacent the slot therein and adjacent the portion of the sleeve opposite from said slot, and means for moving said plug into said sleeve to expand said slot.

12. In an expanding device, a resilient, slotted, tapered sleeve, a plug disposed in said sleeve, said plug engaging the walls of said sleeve on portions thereof and being spaced from the walls of the sleeve at other portions thereof whereby the edges of the slot in said sleeve may be moved toward each other when said plug is in position in the sleeve.

13. In an expanding device, a resilient, slotted, tapered sleeve, a plug disposed in said sleeve, said plug engaging the walls of said sleeve on portions thereof and being spaced from the walls of the sleeve at other portions thereof whereby the edges of the slot in said sleeve may be moved toward each other when said plug is in position in the sleeve, and means for moving said plug into said tapered sleeve to vary the width of the slot in said sleeve.

LEON A. WITTER.
